UNITED STATES PATENT OFFICE.

CHRISTOPHER IBLINGS, OF AKRON, IOWA.

HINGE.

1,067,119.

Specification of Letters Patent.

Patented July 8, 1913.

Application filed October 31, 1912. Serial No. 728,891.

To all whom it may concern:

Be it known that I, CHRISTOPHER IBLINGS, a citizen of the United States, residing at Akron, in the county of Plymouth and State 5 of Iowa, have invented certain new and useful Improvements in Hinges; and I do declare the following to be a full, clear, and exact description of the invention, such as will enable others skilled in the art to which 10 it appertains to make and use the same.

This invention relates to improvements in hinges.

One object of the invention is to provide a hinge designed especially for use with 15 doors which swing on a horizontal pivot and which is provided with means for holding the door in a raised or open position.

Another object is to provide a hinge of this character which is particularly adapted 20 for use in connection with the doors of corn cribs or other slatted doors and in which one of the leaves of the hinges forms the cleats for the door slats and also serves as hasps for fastening the door in closed position.

With these and other objects in view, the invention consists of certain novel features of construction, and the combination and arrangement of parts as will be more fully 25 described and claimed.

In the accompanying drawings: Figure 1 is a perspective view of a portion of one side of a corn crib showing the application of my improved hinges to the door of the crib, 35 the latter being shown in closed position; Fig. 2 is a similar view showing the door in open position; Fig. 3 is an enlarged vertical sectional view through the door and hinge; Fig. 4 is an enlarged horizontal sectional view of one of the hinges taken on the line 4—4 of Fig. 1; Fig. 5 is a similar view with the door in open position and taken on the line 5—5 of Fig. 2. Fig. 6 is a detail perspective view of one of the 45 hinges.

Referring more particularly to the drawings 1 denotes the side of a corn crib and 2 denotes the door thereof to which my improved hinges are applied. The hinges comprise 50 a stationary leaf or member 3 and a swinging or door engaging leaf or member 4. The stationary member 3 is preferably formed of heavy sheet metal and comprises a base plate 5 which is fastened in any suitable manner to the side of the corn crib or 55 other object and which has on its edges out-

wardly extending flanges 6 which are disposed at substantially right angles to the base plate 5 as shown. The flanges 6 are resilient or have a spring action for a purpose hereinafter described. In the inner ends of the flanges 6 are formed alining apertures adapted to receive the pivot bolt or pintle 7 with which the door member 4 of the hinge is pivotally secured to the stationary member 3. The door member or leaf 4 of the hinge is also preferably constructed of heavy sheet metal in the form of a strip of sufficient length to extend across and a short distance beyond the free edge of the door as shown. On the edges of the leaf 4 are outwardly projecting flanges 8 which impart rigidity to the leaf and are also provided for another purpose herein- 60 after described. The leaves 4 are secured to the slats of the door and form cleats for connecting and supporting said slats and at the inner end of the leaves are formed eyes 9 which are disposed between the flanges 6 of the stationary members 3 and receive the pivot bolts or pintles 7 which pivotally connect the leaves of the hinges. In the projecting outer ends of the leaves 4 are formed slots 10 which when the door is in a closed position are adapted to engage eye 70 bolts or staples 11 with which may be engaged fastening pins or pad locks, whereby the door may be fastened or locked in closed position.

The leaves 4 are of suitable width to 75 swing between the flanges 6 of the stationary members 3 of the hinge when the door is swung upwardly to an open position and when in this position the flanges 8 of the leaves 4 are sprung between or into engagement with said flanges 6 which latter grip the flanged edges of the leaves 4 and thereby hold the door in an open position. In order to facilitate the frictional engagement of the flanges 8 on the leaf 4 with the flanges 80 6 on the stationary leaf or member 3 the said flanges 8 are preferably inclined inwardly to a slight extent at their outer edges while the flanges 6 flare or turn outwardly to a slight extent at their outer edges. By thus 85 constructing the leaves or members of the hinge, it will be seen that when the door is swung to an open position the frictional engagement between the flanged edges of the leaves will firmly hold the door open until manually released and swung to a 90 closed position and it will also be seen that 95 100 105 110

the construction of the door members of the 5 hinges forms strong durable cleats for the slats of the door and said door engaging members may be constructed in various lengths to provide supporting cleats for doors of different widths.

From the foregoing description, taken in connection with the accompanying drawings, the construction and operation of the 10 invention will be readily understood without requiring a more extended explanation.

Various changes in the form, proportion and the minor details of construction may be resorted to without departing from the 15 principle or sacrificing any of the advantages of the invention as claimed.

Having thus described my invention, what I claim is:

In a hinge of the character described, a 20 stationary member having its edges bent

outwardly to form substantially right angular gripping flanges, a swinging or door engaging member adapted to project across and to be secured to a door, said member having on its edges outwardly projecting flanges adapted to be swung between the gripping flanges on the stationary member of the hinge when the door is swung open, said gripping flanges being flared outwardly at their outer edges and the flanges on the 25 swinging member turned inwardly to a slight extent to facilitate the engagement of the flanged edges of the hinge members.

In testimony whereof I have hereunto set my hand in presence of two subscribing 30 witnesses.

CHRISTOPHER IBLINGS.
